Primary Examiner — Brett Miller*Assistant Examiner* — Rina J Abdallah(74) *Attorney, Agent, or Firm* — Williams Intellectual Property; Benjamin F. Williams(57) **CLAIM**

The ornamental design for a toddler's cup lid, as shown and described.

DESCRIPTION

FIG. 1 is a top elevation view of my new design; FIG. 2 is a bottom elevation view; FIG. 3 is a front elevation view; FIG. 4 is a rear elevation view; FIG. 5 is a right elevation view; FIG. 6 is a left elevation view; FIG. 7 is a diagonal raised front elevation view; FIG. 8 is a left side elevation view of my design in the environment in which the design is seen to operate; and, FIG. 9 is a diagonal elevation view of my design in the environment in which the design is seen to operate. The portions of FIGS. 8 and 9 shown in broken lines are for the purpose of showing the environment in which the design may be seen and form no part of the claimed design.

1 Claim, 7 Drawing Sheets(56)
